UNITED STATES PATENT OFFICE.

THOMAS RHODUS, OF CHICAGO, ILLINOIS.

RHEOSTAT.

1,230,221.

Specification of Letters Patent. Patented June 19, 1917.

Application filed October 2, 1916. Serial No. 123,214.

To all whom it may concern:

Be it known that I, THOMAS RHODUS, a citizen of the United States of America, and a resident of Chicago, in the county of Cook, 5 State of Illinois, have invented certain new and useful Improvements in Rheostats, of which the following is a specification.

This invention relates to that class of adjustable rheostats forming the subject matter of my prior Letters Patent, No. 1,154,728, dated September 28, 1915, and has for its object to provide a structural formation and combination of parts whereby an effective contact between the annular resistance member and the circumferentially adjustable contact member is constantly and yieldingly maintained, and whereby frictional wear and sparking and burning of the parts in actual use is reduced to a minimum, all as 15 will hereinafter more fully appear.

In the accompanying drawings:—

Figure 1, is a sectional plan view of a rheostat embodying the present invention.

Figs. 2 and 3 are enlarged detail sections 25 on lines 2—2, and 3—3, respectively, Fig. 1.

Similar reference numerals indicate like parts in the several views.

Referring to the drawing, 1 designates a suitable supporting base, carrying the usual 30 insulating slab or rail 4 and the inclosing shell 5, which in turn provides a support and inclosure for the resistance element or member of the apparatus.

The said resistance member, in the present 35 structure, comprises a serial of open and flat spiral windings of resistance wire 6 wound upon an insulating core, preferably of a construction as follows:—

7 designates a flexible flat band core of 40 metal or the like, the overlapping ends of which are secured to a supporting bracket 8, on the insulating slab or rail 4 aforesaid, and preferably in the yielding manner hereinafter described.

45 9 designates a covering of insulating material inclosing the main portion of the core 7 aforesaid, and in turn providing an insulating support for the windows of resistance wire 6 aforesaid.

50 10 designates the attaching bolt by which the resistance element or member aforesaid, is secured in position, and with a view to at-

tain a yielding attachment between the parts, the bolt 10 will pass through the supporting bracket 8, and the overlapping ends of the 55 core 7, and be provided with a yielding cushion or spring 11 interposed between the head or nut of said bolt and the adjacent face of an overlapping end of the core 7, as shown.

12 designates a bearing hub secured centrally on the insulatory rail 4, and providing a journal bearing for a shaft 13 adapted for manual operation.

14 designates an arm fixed on the shaft 13 and carrying on its outer end a roller or 65 drum 15 adapted for rolling contact with the circular inner surface of the resistance member above described.

In the present improvement, the radial length of the arm 14 and its contact roller 70 15 combined, is greater than one-half the internal diameter of the associated circular resistance member, so that at the point of contact of the parts, the roller 15 will effect an outward displacement of the adjacent portion of said resistance member, and the extent of such displacement will depend upon the degree of flexibility of the core 7 of said resistance member and the resiliency of the cushion or spring 11 above described. By 75 80 the described construction, a very efficient electrical contact is maintained between the said parts in a simple and economical manner, and at the same time wear between the contact surfaces is reduced to a minimum. 85

Having thus fully described my said invention, what I claim as new and desire to secure by Letters Patent, is:—

1. In a rheostat, the combination of a flat curved core, a resistance element wound 90 around the core, means for yieldingly holding the core in position, and a circumferentially adjustable non-expansible contact arm pivoted centrally of said core and adapted in its adjustment to displace said core laterally, 95 substantially as set forth.

2. In a rheostat, the combination of a flexible flat curved core, a resistance element wound around the core, means for supporting said core in position, and a circumferentially adjustable non-expansible contact arm pivoted centrally of said core and adapted in its adjustment to displace said core laterally, 100 substantially as set forth.

3. In a rheostat, the combination of a flat curved core, a resistance element wound closely upon the core, means for supporting said core in position, a rolling contact element adapted to make contact with the flat side of said resistance element, and a circumferentially adjustable non-expansible contact

arm pivoted centrally of said core and adapted in its adjustment to move said rolling contact element circumferentially, substantially as set forth. 10

Signed at Chicago, Illinois, this 29th day of September 1916.

THOMAS RHODUS.
